UNITED STATES PATENT OFFICE

JAMES R. KILLEEN, OF DAYTON, OHIO, ASSIGNOR TO FRIGIDAIRE CORPORATION, OF DAYTON, OHIO, A CORPORATION OF DELAWARE

REFRIGERATING APPARATUS

Application filed February 19, 1930. Serial No. 429,788.

This invention relates to improvements in refrigerating apparatus and particularly to improvements in evaporators or refrigerating elements used in mechanically refrigerated cabinets.

It is an object of the present invention to provide an improved refrigerating element or evaporator which can be used in refrigerators of the type in which the cooling section or compartment is relatively long and narrow such as the chambers of large commercial storage cabinets.

More particularly it is an object of the invention to increase the efficiency by insuring the circulation of refrigerant in a relatively long and narrow refrigerating element. In carrying out the above object it is a further object to provide a plurality of ducts or pipes adapted to interconnect spaced headers and to provide cross-over means between the headers whereby the path of flow of the evaporated refrigerant is reduced.

Further objects and advantages of the present invention will be apparent from the following description, reference being had to the accompanying drawings, wherein a preferred form of the present invention is clearly shown.

In the drawings:

Fig. 1 is a vertical cross sectional view of a cold storage cabinet having a cooling unit constructed according to the present invention installed therein;

Fig. 2 is a top view of the improved refrigerating element;

Fig. 3 is a front view of the improved refrigerating element shown in Fig. 2;

Fig. 4 shows a modified form of refrigerating element embodying features of the present invention; and

Fig. 5 is an enlarged sectional view through the refrigerating element taken on the line 5—5 of Fig. 2 but having parts of the tubes broken away.

Horizontal evaporators of the type having a chamber or header connected by a plurality of long refrigerant expansion pipes or ducts have been found inefficient for cooling circulating air if extended beyond a certain length. In relatively long evaporators of this

construction the refrigerant in the central portions of the ducts becomes "oil-logged" or dormant. This dormant condition of the refrigerant, in these portions of the ducts is caused by the great distance which the refrigerant gas is required to travel or flow before it reaches an open path, or a path not flooded or obstructed by liquid refrigerant, which leads to the outlet of the evaporator. The great distance that the refrigerant gas in the central portion of the ducts is required to travel causes liquid refrigerant, in the tubes, nearest the gas outlet or outlets of the ducts, to boil or evaporate rapidly. In order to provide the required refrigeration the ends of the evaporator must be cooled to a very low temperature. When this condition exists within the evaporator, the entire refrigerating system as well as the evaporator is inefficient and produces a non-uniform air circulation within the cabinet being cooled by the evaporator.

My invention is directed to a means of improving the circulation of refrigerant in evaporators of the type hereinbefore described and particularly to overcoming such difficulties which cause inefficiency.

Referring to the drawings Fig. 1 illustrates the improved refrigerating element or evaporator 10 of the invention mounted in operative relation in a cold storage cabinet 11. The cabinet 11 comprises a structure which is relatively wide or long and shallow in depth. The interior of the cabinet 11 is divided into a cooling compartment 12 and a storage compartment 13 by a baffle 14 spaced from and located under the evaporator 10. The baffle 14 is also spaced from the front and rear walls of the cabinet 11 so as to provide flues or passages for the circulation of air from compartment 13 to and over the evaporator 10 located in the cooling compartment 12. The baffle 14 is disposed at an angle and is provided with a gutter 15 at its lower edge which directs moisture, during defrosting of the evaporator 10, to the drain pipe 16 which leads to the exterior of the cabinet. A plurality of doors 17 hinged to the front wall of cabinet 11 permit access to the storage compartment 13. In the particular embodiment

illustrated, the evaporator 10 may be connected by a liquid pipe 18, and a refrigerant gas return pipe 19, to a mechanical refrigerating unit (not shown) of any suitable construction.

Referring in detail to the drawings it will be observed that the improved refrigerating element or evaporator 10 comprises a main header 20 and an auxiliary or additional header 21. A cross-over connection or header 22 is disposed between the headers 20 and 21. The header 22 and the headers 20 and 21 are connected by a duct system composed of a plurality of individual pipes 23. It is one of the features of the invention to so arrange these ducts that some are below the liquid refrigerant level and some above the liquid level maintained in the evaporator. Such arrangement of the ducts provides a relatively open path to the outlet of the evaporator throughout the length thereof to permit refrigerant gas to flow freely.

As above stated liquid refrigerant is present in evaporator 10 and is covered with a thin layer of oil 24 which oil is circulated to the evaporator along with liquid refrigerant during operation of the refrigerating mechanical unit. The level of liquid refrigerant in the evaporator 10 is controlled by any suitable float valve mechanism 25 and is maintained substantially at the height indicated at 26. In the particular type of evaporator illustrated, by way of example, the liquid refrigerant inlet to the evaporator is indicated by 18a and the suction or outlet by 19a. The liquid refrigerant will pass through the ducts 23 connecting the header 22 and the heads 20 and 21 and will lie in the header 21 and header 22 at substantially the same level as in the header 20 which houses the float valve mechanism 25.

The cross over means or header 22 may be formed of two cup members 30 and 31 (see Fig. 5) having apertures in their end walls for receiving the ends 32 of the pipes 23 which are soldered to the header 22. The cup members 30 and 31 are each provided with an outwardly turned flange 34 which flanges are clamped between clamping rings 35 by bolts 36. A gasket 37 located between the flanges 34 and the rings 35 seal the joint in the tank 22 from refrigerant leaks. Each of the headers 20 and 21 are provided with a plurality of holes 40 in one side wall thereof. The upper and lower rows of the holes 40 have a cover member 41 secured to the boiler in any suitable manner such as by welding thereto. Each cover member 41 is provided with holes 42 which receive the ends 43 of pipes 23 which communicate with the interior of the headers through the holes 40 provided therein. The header 22 being detachable in the manner described permits longer or shorter rear sections to be attached to the section of the evaporator containing

the float valve mechanism for varying the length of the evaporator.

In Fig. 4 I have shown a modified form of the evaporator in which the header 22 located between the headers 20 and 21 is not detachable. The pipes 23 extend from the rear wall of the main horizontal header 20 so as to provide a very narrow evaporator. This narrow evaporator may be desirable for use in a more shallow compartment than that in which my preferred type is used. However the features of my invention are also important in this type of evaporator.

In order to facilitate the exchange of heat between the air and the ducts or pipes 23 of the refrigerating element 10 the connecting ducts are provided with fins 45. These fins are disposed transverse to the longitudinal axis of the element, that is, substantially parallel to the side walls of the headers in the evaporator of the preferred type, and substantially parallel to the end walls of the headers in the evaporator of the modified form. The fins 45 are spaced apart all along the length of the connecting ducts 23. These fins are preferably forced on the tubes or ducts 23 and secured in place by means of small tubulars or flanges 46 punched out of the fins and, if desired, the fins may be soldered to the ducts to insure good thermal contact.

The intermediate header 22 of the improved refrigerating element permits the escape of refrigerant gas from the lower liquid refrigerant ducts to the gas return ducts leading to header 20. In this manner the ebullition throughout the entire length of the ducts is sufficient to prevent "oil-logging" of the lower liquid refrigerant ducts.

From the foregoing it is apparent that I have provided for the manufacture of relatively long narrow evaporators the parts of which are all substantially in the same horizontal plane and in which an efficient circulation of refrigerant will occur. Furthermore my improved evaporator will be maintained at substantially the same temperature throughout its length thus insuring a uniform circulation of air cooled by such evaporator while at the same time effecting an efficient return of lubricant from the evaporator to the compressor of the mechanical refrigerating unit.

While the form of embodiment of the invention as herein disclosed, constitutes a preferred form, it is to be understood that other forms might be adopted, all coming within the scope of the claims which follow.

What is claimed is as follows:

1. A horizontally elongated evaporator of a refrigerating system comprising in combination, a header having an inlet and an outlet adapted to be connected to a refrigerant circulating means, a second header spaced from the first header, a plurality of ducts in-

- terconnecting said headers, said headers containing a quantity of liquid refrigerant and having a gas space, a plurality of ducts extending outwardly from said second header, 5 certain of said ducts being disposed above the liquid refrigerant level in said evaporator and certain other of said ducts being disposed below the liquid level, means forming a fluid connection for the flow of gaseous refrigerant 10 from the duct disposed below the refrigerant level and the duct above the refrigerant level, said headers and ducts being substantially within the same horizontal plane.
2. A horizontally elongated evaporator of 15 a refrigerating system comprising in combination, a header having an inlet and an outlet adapted to be connected to a refrigerant circulating means, a second header spaced from the first header, said headers containing 20 a quantity of liquid refrigerant and having a gas space, a plurality of ducts interconnecting said headers, a plurality of ducts extending outwardly from said second header, certain of said ducts being disposed above 25 the liquid refrigerant level in said evaporator and certain other of said ducts being disposed below the liquid level, and a third header connected with the ends of said second mentioned ducts.
3. A horizontally elongated evaporator of 30 a refrigerating system comprising in combination, a header having an inlet and an outlet adapted to be connected to a refrigerant circulating means, a second header spaced from 35 the first header, said headers containing a quantity of liquid refrigerant and having a gas space, a plurality of ducts interconnecting said headers, a plurality of ducts extending outwardly from said second header, certain 40 of said ducts being disposed above the liquid refrigerant level in said evaporator and certain other of said ducts being disposed below the liquid level, and a third header connected with the ends of said second mentioned ducts, all of said ducts and said third 45 mentioned header being within the height of the walls of said first and second mentioned headers.
4. A horizontally elongated evaporator of 50 a refrigerating system comprising in combination, a header adapted to contain liquid refrigerant, means within said header for preventing liquid from rising above a certain level, a second header spaced from said first 55 mentioned header, a plurality of duct means connecting both of said headers, some of said plurality of duct means being disposed above the liquid refrigerant level and some other of said plurality of duct means being disposed 60 below the liquid level, cross-over means between said headers and connected with all of said duct means extending between said headers.
5. A horizontally elongated evaporator of 65 a refrigerating system comprising in combi-
- nation, a header adapted to contain liquid refrigerant, means within said header for preventing liquid from rising above a certain level, a second header spaced from said first mentioned header, a plurality of duct means 70 connecting both of said headers, some of said plurality of duct means being disposed above the liquid refrigerant level and some other of said plurality of duct means being disposed below the liquid level, cross-over means between said headers and connected with all of said duct means extending between said headers, said cross-over means and said duct means being substantially within the same horizontal plane of said headers. 80
6. A horizontally elongated evaporator of 85 a refrigerating system comprising in combination, a header adapted to contain liquid refrigerant, means within said header for preventing liquid from rising above a certain level, a second header spaced from said first mentioned header, duct means connecting both of said headers, certain of said duct means being disposed above the liquid refrigerant level and certain other of said duct 90 means being disposed below the liquid level, a third header disposed between said first and second mentioned headers and connected with said duct means, said third mentioned header and said duct means being substantially within the height of said first and second mentioned headers. 95
7. A relatively long narrow evaporator of 100 a refrigerating system comprising in combination, a header adapted to contain liquid refrigerant, means within said header for preventing liquid from rising above a certain level, duct means extending outwardly from a wall of said header, said duct means connected with a second header, duct means 105 extending from said second header in the same direction as said first mentioned duct means, certain of said duct means being disposed above the liquid refrigerant level in said evaporator and certain other of said duct 110 means being disposed below the liquid level, and a third header connecting the ends of said second mentioned duct means.
8. A relatively long narrow evaporator of 115 a refrigerating system comprising in combination, a header adapted to contain liquid refrigerant, means within said header for preventing liquid from rising above a certain level, duct means extending outwardly from a wall of said header, said duct means connected with a second header, duct means 120 extending from said second header in the same direction as said first mentioned duct means, certain of said duct means being disposed above the liquid refrigerant level in said 125 evaporator and certain other of said duct means being disposed below the liquid level, and a third header connecting the ends of said second mentioned duct means, all of said duct means and said third mentioned 130

header being within the height of said first and second mentioned headers.

9. A horizontally elongated evaporator comprising a tube section forming the major heat transfer surface of the evaporator in contact with the liquid refrigerant, said section including a plurality of long, slender and horizontally disposed liquid refrigerant conveying tubes, a header for supplying liquid refrigerant to the tube section, said header having a gas space, a plurality of gas conduits connected with the header and extending longitudinally of the tube section, and cross-over duct means interposed between the ends of the section and connected with all of said plurality of liquid refrigerant tubes and with all of said plurality of gas conduits for conveying vaporized refrigerant from a plurality of said tubes to said gas conduits.

20 In testimony whereof I hereto affix my signature.

JAMES R. KILLEN.
